UNITED STATES PATENT OFFICE.

CARL W. LARSON AND CARL OLOFSON, OF JAMESTOWN, NEW YORK, ASSIGNEES TO DAHLSTROM METALLIC DOOR COMPANY, OF JAMESTOWN, NEW YORK, A CORPORATION OF NEW YORK.

METALLIC DOOR AND THE LIKE.

1,166,228.

Specification of Letters Patent. Patented Dec. 28, 1915.

Application filed February 23, 1912. Serial No. 679,441.

To all whom it may concern:

Be it known that we, CARL W. LARSON and CARL OLOFSON, both citizens of the United States, and residents of Jamestown, in the 5 county of Chautauqua and State of New York, have invented new and useful Improvements in Metallic Doors and the like, of which the following is a specification.

Our invention relates to improvements in 10 metallic doors and it has for its object the provision of a simple, inexpensive and durable door, and in which the panels and stiles are formed in piece and the panels so shaped or fashioned to provide reinforcements 15 serving as bearings to which the rails are applied.

Another object of our invention is to provide reinforcements for the intermediate rail and to so secure them to the opposite 20 walls of the panel that all riveting may be dispensed with; also to provide interlocking means which prevent movement lengthwise 25 of the opposite panel walls or members; and to otherwise improve on metallic doors now in use.

With these and other objects in view the invention consists in the construction, arrangement and combination of parts to be hereinafter described and particularly pointed out in the subjoined claims.

In the drawings,—Figure 1 is a side elevation of a door constructed according to our invention. Fig. 2 is an enlarged horizontal section taken on line $v-v$, Fig. 1. 35 Fig. 3 is an enlarged vertical section taken on line $w-w$, Fig. 1. Fig. 4 is an enlarged vertical section taken on line $x-x$, Fig. 1. Fig. 5 is an enlarged vertical section taken on line $y-y$, Fig. 1. Fig. 6 is an enlarged 40 horizontal section taken on line $z-z$, Fig. 1. Fig. 7 is an enlarged side elevation of one corner of the door, with a part of one side of the upper rail broken away. Fig. 8 is a horizontal section of a door in slightly 45 modified form.

Referring now to the drawings in detail in which like numerals of reference refer to like parts in the several figures, the door comprises stiles 9, a top rail 10, an intermediate rail 11, and a bottom rail 12 forming panels 13, and 14. The stiles and panels are formed of one or two sheets of metal as shown in Figs. 2 and 8, but we preferably employ two sheets, each sheet being bent or 55 rolled to provide one side and one edge of

the door, while the other sheet is bent to from the other side and edge. Each sheet is bent or rolled to provide one of the edge walls 15, one of the side walls 16 of each stile, one of the panel walls 17, and two of 60 the moldings 18 connecting the panel with the stiles. These sheets are interlocked at diametrically opposite edges by interlocking seams 19 wholly within the stiles.

In the modification shown in Fig. 8 in 65 which the stiles and panels are formed of a single sheet of metal, the seam 20 only is employed, it being preferably located at one of the outer edges of the door. The stiles are therefore made hollow while the opposite 70 panel walls 17 are separated from each other and between them is interposed asbestos 21 or other fireproof and non-conducting material. Near the upper and lower 75 ends of the panel walls, opposite projections 22, 23, are provided which are formed by bending the metal of the panel walls into oppositely-disposed channels and the upper end of one wall is bent at a right angle to provide a spacing flange 24 while the lower 80 end of the other wall is oppositely bent to provide a spacing flange 25. The lower end of said first-mentioned panel wall is re-bent, as at 85 26, to embrace the lower end of the other co-operating wall while the upper end 85 of said last-mentioned wall is re-bent, as at 27, to embrace the upper end of said first-mentioned panel wall. Screws 28 pass through the re-bent portions of the opposite 90 walls and take into the spacing flanges 24, 25, thus securely holding the panel walls against movement lengthwise. Fitting over the opposite ends of said panel walls are the upper and lower rails, the sides of which 95 bear against the projecting portions 22, 23 of said panel walls and are spot welded thereto or otherwise fastened, thus being rigidly braced so that they can neither bulge outward nor be forced inward. Each of 100 these rails are formed of two strips of metal bent or rolled along their inner marginal portions into moldings 29, preferably corresponding in shape to the moldings 18 connecting the stiles with the panel members, the inner extremities of said strips of metal 105 being bent into angular form, as at 30, in which are fitted stiffening bars 31, welded or otherwise fastened to the panel members and to which the angular portions of the moldings are welded or otherwise fastened. 110

Interposed between the side walls of the upper and lower rails are outwardly-facing channel bars 32 around which the outer marginal portions of said side walls are bent to lie against the inner faces of the sides of said channel and against the faces of the inner walls thereof and fitting between the re-bent portions of said side walls are inwardly-facing channel bars 33 having their edges bearing against the extremities of the side walls of said rails and the outer faces thereof flush with the bent edges of said side walls. Screws 34 are passed through the channel bars 33 and take into the channel bars 32, thus securely locking the two channels together and fastening the walls of the rails at their outer edges between said channels.

The intermediate rail 11 is formed of two strips of metal 35 and 36, one at each side of the panel, the marginal portions of the strips being bent or rolled to form moldings 37 corresponding to the moldings of the stiles and the upper and lower rails and like said upper and lower rails they have angular portions 38 reinforced by metallic bars 39 welded or otherwise fastened to the panel walls and to which the angular portions of said intermediate rail are welded or otherwise fastened.

Within the space inclosed by this intermediate rail we reinforce the panel walls to prevent their bulging out or being pressed in and we preferably employ for this purpose a Z-bar 40 which we secure to the inner face of one of the panel walls, and to the inner face of the other panel wall we secure a plate 41 having an offset portion 42 separated by a space from the panel wall to which it is secured and in which space fits the free flange 43 of the Z-bar. Between the panel walls and the opposite side walls of the intermediate rail we interpose reinforcing bars 44 in the form of Z-bars, one of the parallel flanges of each bar being welded or otherwise secured to the inner face of the adjacent side wall of the rail and the other flange to the coöperating panel wall. For the purpose of permitting these reinforcing bars 44 to be spot welded, the panel walls are provided with openings 45, 46 directly above said bars so that a part of a spot welder may be passed through these openings to fasten the outer flanges of the said bars to the panel walls.

As clearly shown in Fig. 7, the channel bars 32, 33 extend to the outer edge walls of the stiles and where the ends of the rails meet the stiles, the latter and the molding 18 are cut away, as at 47, the molding of the stiles and rails being cut obliquely where they meet, as at 48, to make a finished joint. It is to be noted therefore that by cutting the molding of the stiles and a portion of the stiles away where the upper and lower

rails join them, the panel walls are separated from the side walls of the stile within the rails, as at 49, to provide free ends for the panel walls which permit of readily bending them into channel shape, as shown at 22, 23, and also brings the upper and lower edges of the panel walls into the rails a sufficient distance to provide space for the placing of the channels 32, 33 between the side walls of the rails and stiles. 70

Having thus described our invention, what we claim is,—

1. A metallic door or the like having hollow stiles and rails, a panel bounded by said stiles and rails and extending into said rails, 80 said panel comprising two panel members bent upon themselves near opposite ends to provide projecting portions within said rails against which the sides of the latter bear, said panel portions being spaced from the sides of said rails at opposite sides of said projecting portions. 85

2. A metallic door or the like having hollow stiles and rails, and a panel bounded by said stiles and rails and comprising two 90 panel members, the metal of said panel extending into said rails and each panel member being bent upon itself to provide channel-shaped projecting portions against which the side walls of said rails bear, said panel being spaced from the sides of said rails at opposite sides of said channel-shaped projecting portions. 95

3. A metallic door or the like comprising hollow stiles and rails, and a panel bounded by said stiles and rails and having the ends of the material forming said panel extending into said rails and bent upon itself transversely near opposite ends to provide projecting channels against which the sides 100 of said rails bear and are secured, said panel being spaced from the sides of said rails at opposite sides of said projecting channels. 105

4. A metallic door or the like having hollow stiles and rails, and a panel bounded by said stiles and rails and comprising two 110 panel walls separated from each other, one end of each panel wall being bent at right angles to provide a spacing flange and the other ends of said walls being re-bent upon themselves to embrace the flanged end of the coöperating wall. 115

5. A metallic door or the like having hollow stiles and rails, and a panel bounded by said stiles and rails, said panel comprising two panel walls separated from each other and one wall being bent at right angles at its lower end and the other at its upper end to form spacing flanges, said first-mentioned wall having its upper end re-bent to embrace the upper end of the other wall and said other wall having its lower end re-bent to embrace the lower end of said first-mentioned wall, and screws taking into the re- 120 125 130 135 140 145 150 155 160 165 170 175 180 185 190 195 198

bent end of said panel walls and entering the spacing flanges of the coöperating wall.

6. A metallic door or the like comprising hollow stiles and rails, and a panel bounded by said stiles and rails, said rails being formed of sheet metal to provide opposite walls, a channel bar between the side walls of each rail, said rails having their outer marginal portions re-bent to fit around the side walls of said channel bar and against the inner wall of the same, a second channel bar fitting between and in contact with the re-bent portions of said side walls, and means for connecting said channel bars together.

7. A metallic door or the like having hollow stiles and rails, and a panel bounded by said stiles and rails, said panel and stiles having opposite side walls separated by an intervening space and each panel wall being in piece with the side walls of the stiles on the same side of the door, the upper ends of said panel walls being separated from the upper ends of said stiles and being bent transversely to provide opposite projecting portions, and rails fitting over the ends of said panel walls and in contact with the opposite projecting portions thereof.

8. A metallic door or the like having hollow stiles and rails, and a panel bounded by said stiles and rails, said panel and stiles comprising opposite side walls separated by an intervening space, and projecting interlocking members on the inner faces of said panel walls.

9. A metallic door or the like having hollow stiles and rails, and a panel bounded by said stiles and rails, said panel and stiles comprising opposite side walls separated by an intervening space, one of said panel walls having a transversely disposed Z bar secured to its inner face and the other wall having a bar provided with an off-set portion between which and the panel wall from which it extends the bar of the opposite panel wall is engaged.

10. A metallic door or the like comprising hollow stiles and rails, an intermediate rail, and a panel bounded by said stiles and rails,

the stiles, rails and panel having opposite side walls separated by an intervening space, a filling in the space between the walls of said panel, interlocking elements secured to the inner faces of said panel walls, and reinforcing bars between said panel walls and the side walls of said intermediate rail.

11. A metallic door or the like comprising hollow stiles, an upper, a lower, and an intermediate rail, and panels bounded by said stiles and rails, said panel comprising two panel walls separated by an intervening space, said upper and lower rails fitting over the ends of said panel walls and said intermediate rail comprising two parts applied to opposite sides of said panel walls, Z shaped elements between the panel walls and the side walls of said intermediate rail and secured to both, interlocking elements secured to the inner faces of said panel walls, and means provided in the construction of said panel walls to permit the insertion of a welding instrument therebetween to weld said Z shaped elements in place.

12. A metallic door having two separated panel walls provided with openings, an intermediate rail comprising two parts applied to the outer opposite edges of said panel walls and covering said openings, a Z bar secured to the inner face of one of said panel walls and having one of its flanges free, a bar secured to the inner face of the other panel wall and off-set between its marginal portions to engage the free flange of said Z bar, and a Z bar between each panel wall and the adjacent side wall of the intermediate rail, said last-mentioned Z bars being adjacent the openings in said panel walls to permit of securely welding them in position.

In testimony whereof, we have affixed our signatures in the presence of two subscribing witnesses.
